UNITED STATES PATENT OFFICE.

ADOLF PFAENDLER, OF BROOKLYN, NEW YORK.

DESIGN FOR FABRIC.

SPECIFICATION forming part of Design No. 36,080, dated September 16, 1902.

Application filed July 24, 1902. Serial No. 116,879. Term of patent 3½ years.

To all whom it may concern:

Be it known that I, ADOLF PFAENDLER, a citizen of the United States, residing at Brooklyn borough, New York city, in the county of Kings and State of New York, have invented a new, original, and ornamental Design for a Fabric, of which the following is a specification.

My invention relates to a new, original, and ornamental design for a fabric and is illustrated in the accompanying drawing, which is a face view of the fabric ornamented according to my design.

The design consists of a fabric ornamented by figures of boy and girl dolls arranged as shown in the drawing.

In the said drawing the reference-letter *e* indicates the fabric, which is ornamented by a back view of a boy doll *a*, the front view of which is shown at *a'*.

b' indicates a front view of a girl doll, and *b* a back view thereof.

c' indicates a front view of a girl doll, and *d'* a front view of a boy doll.

The representations of front and back views 25 of boy and girl dolls are arranged in sets of three in two horizontal series, one above the other. Below said representations of the boy and girl dolls appear back views of boy and girl dolls arranged angularly on the fabric, 30 with the heads arranged along the longitudinal median line of the fabric, with the feet pointing toward the opposite edges thereof.

The letter *f* represents dotted lines surrounding the several figures of the dolls. 35

My design presents a fabric having a distinguished and ornamental appearance.

What I claim as new, and desire to secure by Letters Patent, is—

The ornamental design for a fabric, substantially as herein shown and described.

In testimony whereof I have hereunto set my hand in the presence of two subscribing witnesses.

ADOLF PFAENDLER.
